UNITED STATES PATENT OFFICE.

HARRY J. HAYS, OF WASHINGTON, DISTRICT OF COLUMBIA.

GRINDING OR POLISHING MACHINE.

Application filed January 8, 1924. Serial No. 685,000.

My invention relates to machines for grinding or polishing sheet material, and has particular reference to an improved apparatus especially adapted for use in grinding or polishing sheet or plate glass and the like.

An object of my invention is to provide an improved machine for grinding or polishing sheet material, in which the rough sheet or plate travels progressively through the machine past a series of grinding and polishing units, where one or both sides of the sheet is ground and polished to the desired thickness and degree of surface finish.

15 A further object of my invention is to provide a grinding or polishing machine having novel and simple means for receiving and conveying the sheet through the machine past a series of opposed grinding elements, which are so constructed and arranged that when the sheet first enters the machine, it will be acted upon by a relatively coarse abrasive material and as it travels through the machine, will be progressively subjected to the action of finer abrasive and polishing materials, so that when the sheet leaves the discharge end of the machine, the same has been ground and finished to a predetermined thickness and the outer surfaces have received the required polish.

25 A further object of my invention is to provide a grinding or polishing machine for sheet material, in which the faces of each pair of grinding or polishing disks are oppositely disposed, and in which novel means are provided for continuously feeding and re-feeding abrasive or polishing material to the working faces of the said disks of one or more units of the machine.

30 A still further object of my invention is to provide a machine of the above mentioned character having novel means for adjusting the grinding or polishing disks to accommodate different thicknesses of sheet or plate material, and further to provide a novel means for permitting the machine to grind and polish different widths of sheets or plates.

35 In the accompanying drawings forming a part of this specification, in which like numerals are employed to designate like parts throughout the several views,

40 Figure 1 is a plan view, partly in section, showing two grinding or polishing units;

Figure 2 is a side elevation of the machine, and,

Figure 3 is a transverse sectional view of the machine taken on the line 3—3 of Figure 1.

45 Referring to the drawings, wherein for the purpose of illustration is shown a preferred embodiment of the invention, the numeral 1 designates the upright members of the frame of the machine, each having feet 60 2 adapted to be secured to a floor or other supporting structure. These upright members 1 are joined by the longitudinally extending beams 3 and 4 (see Figure 2) and by the transverse beams 5. The elements 65 thus designated by the numerals 1 to 5 inclusive constitute the frame of the machine units, and it is to be understood that a number of these frames are to be placed in end-wise relation to constitute a complete machine, the number of such units depending upon the nature of the sheet material being worked upon and the surface finish or polish required.

50 Slidably mounted upon the opposite sides 80 of each leg 1, are the vertically-adjustable bearing blocks 6, supporting the transverse shafts 8, on which are mounted the idler rollers or guides 7. To provide for the vertical adjustment of these idler rollers or 85 guides 7, I provide guide ways 9 on each side of the legs 1 in which the bearing blocks 6 are vertically adjustable. The bearing blocks are moved up and down by a system of adjusting links and levers, comprising upper links 10 pivotally connected to the bearing blocks 6 and lower links 10^a pivotally mounted on transverse shaft 11, which passes through the lower longitudinal beam 4. The inner ends of the links 10 and 10^a 90 are pivotally connected to the longitudinally extending operating rod 12, as clearly shown in Figure 2, and it is thus obvious that longitudinal movement of the operating rod 12, which may be accomplished by 95 any suitable gear or lever means, will cause a vertical movement or adjustment of the bearing blocks 6 and guide or idler rollers 7.

100 For causing the sheet material to feed or travel through the machine, I provide 105 aligned pairs of feed rollers 14, each of which consist of an elastic cylinder of rubber 15, vulcanized to a vertically-extending drive shaft 16, rotatably mounted in an upper bearing located in the connecting brace 110

17, and in a lower thrust bearing 18, located in the lower longitudinal beam 4. At the lower end of each shaft 16, is keyed a spur gear 19, the gears of each co-acting pair of feed-rollers being in mesh and one of said gears 19 being driven by a worm gear 20, mounted upon a longitudinally extending drive shaft 21, driven by a suitable source of power such as an electric motor or the like, 10 not shown.

The grinding or polishing elements of my improved machine comprise opposed disks 22, each mounted at the inner end of a transversely extending tubular drive shaft 23, to 15 which the disks are secured by the lock-nut 24. The drive shaft 23 is rotatably mounted in bearings 25 and 26, between which is located the driving pulley 27, which is free to move longitudinally of the shaft but which 20 is keyed to rotate therewith. To provide means whereby the distance between the opposed faces of the grinding or polishing elements 22 may be varied to accommodate various thicknesses of sheet or plate material 25 28, I mount on the tubular drive shafts 23 loose collars 30, on opposite sides of which are located the ball thrust bearings 31, confined between collars 32, rigidly secured to the shafts 23. To accomplish the axial 30 movement of the shafts 23 to vary the distance between the faces of opposed grinding elements 22, I provide operating or adjusting levers 33, the lower ends of which are pivotally connected near the base of the legs 35 1, and the upper ends of which are forked to engage opposite sides of the loose collars 30. The outward movements of the levers 33 is restricted by the coil springs 34, while the inward movement of the levers is limited and 40 controlled by the adjustable stop 29. It is thus obvious that the grinding and polishing disks 22 are free to move outwardly against the tension of the springs 34 and that the distance between the opposed faces of the 45 disks is regulated and controlled by the positioning or adjustment of the stop 29.

Positioned beside the machine is a series of vertically arranged, endless bucket conveyors 35, which deliver the abrasive material such as sand, emery, carborundum, or the like, through the chutes 36, into the hoppers 37, from whence it flows through the delivery pipes 38, through the hollow shafts 23 to the faces of the grinding or polishing 50 disks 22. The chutes 38 from each supply hopper may lead to one, two, three or more of the grinding units, depending upon the requirements of the machine and the particular sheet material being worked upon, each 55 of the chutes 38 leading to the outer ends of the hollow shafts 23 to which they are connected by suitable stuffing boxes 39.

Each of the grinding units 22 is enclosed and separated by suitable housings or casings, each comprising a box-like structure

40, closed by a top 41, and each having a lower discharge chute 42, leading from the casings to the bottoms of the conveyors 35. The opposite ends 43 of the casings 40 are each provided with an elongated slot or 10 opening, the marginal edges of which are provided with rubber or leather wipers 44, which prevent the granular abrasive material from escaping from the housings 40 and which wipe or clean the surfaces of the plate 75 or sheet as it passes through the machine to the next grinding or polishing unit.

Referring to the operation of my improved machine, I will, for illustration, describe the same as used to grind and polish sheet or 80 plate glass suitable for windows, automobile windshields, mirrors, desk and table covers, and the like. Assume that for this particular use, four of the separate units shown in Figure 1 of the accompanying drawings are 85 placed end to end so that the faces of the several grinding and polishing units 22 are in perfect alignment. The first step of the operation consists in adjusting or regulating the distance between the opposed faces of 90 each of the several grinders or polishers 22 so that the sheet or plate 28 will be ground and polished to the required thickness. This adjustment is accomplished by movement of the stops 29, which move the levers 33 and 95 thus cause axial movement of the tubular drive shafts 23, to which the grinding or polishing disks 22 are attached. The next step is to move the longitudinally extending rods 12, which act through the levers 10 and 100 10^a and cause vertical movement of the bearing blocks 6 and idler rollers 7, on which the lower edge of the sheet 28 is supported. The position of the idler rollers 7, of course, depends upon the width of the plate or sheet 105 being worked upon. A relatively coarse abrasive compound such as emery, sand, carborundum, or the like is now inserted into the hopper 37 of the first unit of the assembled machine and sufficient water is 110 added to assist in the circulation of the abrasive compound and in the initial grinding operation. Into the hopper 37 of the next successive unit is inserted a like quantity of wet abrasive material of a finer 115 grade than used in unit number 1, and into the hopper of the third unit of the assembly is placed a like quantity of abrasive material of a still finer grade. Hopper 37 of the fourth or last unit of the assembled machine 120 is supplied with a quantity of fine pumice, rouge, or other high grade polishing material.

The motive power for operating the machine is now applied to the shaft 21, which 125 drives the feed rollers 15; to the pulleys 27, which rotate the grinding or polishing disks 22; and to the pulleys 35^a which drive the conveyors 35. The sheet 28 is now placed in upright position with its lower edge resting

on the first idler roller 7 and is then manually moved until it contacts with the first pair of feed rollers 14 which frictionally engage the sides of the sheet and draw the sheet into the machine, where it meets successive pairs of driven feed rollers, which feed the plate or sheet 28 through the entire length of the assembled machine.

As the sheet 28 enters the machine the first 10 two grinding units act upon opposite surfaces of the sheet and due to the relatively coarse abrasive employed in this first unit, the sheet is given its initial surface grinding. The grinding disks 22 are free to move apart 15 a sufficient distance to accommodate the thickness of the rough plate 28, and are under the tension of the spring 34, which tends to draw the disks together until the arms 33 strike the adjustable stops 29, which control 20 the inward movement of the grinding or polishing disks 22. The abrasive material supplied to the disks 22 through the hollow shaft 23 is confined within the housing or casing 40 and drops into the inclined chute 25 42 and into the lower end of the conveyor 35, the driven endless conveyor elevating the material and continuously feeding the same abrasive to the hoppers 37 for re-use, which re-use continues until the abrasive material 30 has become too fine for use in this first unit.

After the sheet has been given its initial grinding in the first unit, it is fed forward to the second unit where it again is engaged 35 by the opposed grinding disks 22 which are continuously fed with abrasive material in the same manner and by the same means employed in the first unit, the only difference being that the abrasive material employed in 40 this second unit is of a finer grade to impart a smoother and more perfect finish to the surfaces of the sheet. After leaving this second unit, the sheet is fed by the feed rollers 14 to the third unit where a similar 45 grinding operation takes place with a still finer grade of abrasive material. Upon entering the fourth unit, the sheet passes between two pairs of polishing disks each supplied, in the same manner and by the same 50 means as in the previous units, with a finishing or polishing material such as pumice, rouge or the like. The sheet is then discharged from the end of the machine.

It will thus be seen that I have provided 55 an improved machine for grinding or polishing sheet material, in which the rough or unfinished sheet is fed into the machine; passes through a series of successive grinding and polishing elements; and is discharged from the machine in a highly polished and finished form. By passing the sheet through the machine, in the manner above described, where it is first subjected 60 to the grinding action of a relatively coarse 65 abrasive material, next to the grinding ac-

tion of a finer grade of abrasive, next to the grinding or polishing action of a still finer grade, and finally to the finishing action of a polishing powder or rouge, I provide a complete and satisfactory machine and method for accomplishing the purposes set forth and one which can be employed with the minimum of expense and labor. The continuous use of the abrasive material in each of the several units effects a marked saving in the cost 75 of operation. When the abrasive compound used in the first units of the machine has been used for a considerable length of time, it will be found that the granules or particles have been so reduced in size that it is no longer 80 satisfactory to perform the initial grinding actions. This abrasive is then transferred to the next succeeding unit of the assembled machine, where it is re-used to perform successive grinding and polishing operations. 85

It is to be understood that while I have described the assembled machine as consisting of four units, that I am not restricted to this particular number and that various combinations of two, three, four, or more 90 units may be employed to suit the character of the sheet material being worked and the finish or polish required. I have chosen to describe my machine as used for grinding and polishing plate or sheet glass, but the 95 same is well adapted for use in grinding and polishing sheet metal, slate, marble, stone, wood, and the like. It is to be further understood that the form of my invention herein shown and described is to be taken 100 as a preferred example of the same, and that various changes in the shape, size, and arrangement of parts may be resorted to, without departing from the spirit of my invention or scope of the subjoined claims. 105

Having thus described the invention, I claim:—

1. In a grinding or polishing machine for sheet material, the combination with a supporting frame, of a series of rotary grinding or polishing elements mounted on said frame, feed rollers for feeding the sheet through the machine past the several grinding or polishing elements, idler rollers for supporting the lower edge of the sheet material, and means for adjusting the vertical position of said idler rollers to accommodate varying widths of sheet material and to bring the center of the sheet material opposite the center of the faces of said grinding or polishing elements during its travel through the machine. 115

2. In a grinding or polishing machine for sheet material, the combination with a supporting frame having upright leg members, of a series of rotary grinding or polishing elements mounted on said frame, feed rollers for feeding the sheet through the machine past the several grinding or polishing elements, bearing blocks slidably mounted 120 125 130

on the upright leg members of the frame, idler rollers carried by said bearing blocks for supporting the lower edge of the sheet material, and means for adjusting the vertical position of said bearing blocks and the idler rollers carried thereby to accommodate varying widths of sheet material and to bring the center of the sheet material opposite the center of the faces of the rotary grinding or polishing elements during its travel through the machine.

3. In a grinding or polishing machine for sheet material, the combination with a supporting frame having upright leg members, of a series of rotary grinding or polishing elements mounted on said frame, feed roll-

ers for feeding the sheet through the machine past the several grinding or polishing elements, bearing blocks slidably mounted on the upright leg members of the frame, ²⁰ idler rollers carried by said bearing blocks for supporting the lower edge of the sheet material, links connected to each of the said bearing blocks, and a common operating rod connected to said links for simultaneously ²⁵ adjusting the vertical position of said bearing blocks and the idler rollers carried thereby to accommodate varying widths of sheet material.

In testimony whereof I hereunto affix my ³⁰ signature.

HARRY J. HAYS.
